US00D860202S

(12) **United States Design Patent** (10) **Patent No.:** **US D860,202 S**
(45) **Date of Patent:** **** Sep. 17, 2019**

(54) **HANDHELD CONTROLLER**

(71) Applicant: **Tactual Labs Co.**, New York, NY (US)

(72) Inventors: **Ricardo Jorge Jota Costa**, Toronto (CA); **Bruno Rodrigues De Araujo**, Toronto (CA); **David Holman**, Toronto (CA)

(73) Assignee: **Tactual Labs Co.**, New York, NY (US)

(**) Term: **15 Years**

(21) Appl. No.: **29/601,600**

(22) Filed: **Apr. 24, 2017**

(51) **LOC (12) Cl.** **14-02**

(52) **U.S. Cl.** USPC **D14/388**

(58) **Field of Classification Search**

USPC D14/388, 218, 454, 299, 496, 400, 401, D14/402, 405, 409, 410; D21/333; D13/168

(57) **CLAIM**

We claim the ornamental design for a handheld controller, as shown and described.

DESCRIPTION

FIG. 1 is a perspective view of a handheld controller, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view of a second embodiment of our new design;

FIG. 9 is a front view thereof;

FIG. 10 is a rear view thereof;

FIG. 11 is a left-side view thereof;

FIG. 12 is a right-side view thereof;

FIG. 13 is a top view thereof;

FIG. 14 is a bottom view thereof;

FIG. 15 is a perspective of a third embodiment of our new design;

FIG. 16 is a front view thereof;

FIG. 17 is a rear view thereof;

FIG. 18 is a left-side view thereof;

FIG. 19 is a right-side view thereof;

FIG. 20 is a top view thereof; and,

FIG. 21 is a bottom view thereof.

The discontinuous shade lines indicate the character and contour of the surfaces represented, not to be confused with surface ornamentation.
